FLEXIBLE DRINKING STRAW

William Nardone, Revere, Mass., assignor to Sweetheart Plastics, Inc., Wilmington, Mass., a corporation of Maryland

Continuation-in-part of design application Ser. No. 7,638, June 29, 1967, now Patent No. 211,226, dated May 28, 1968. This application Jan. 18, 1968, Ser. No. 10,203

Term of patent 14 years

Int. Cl. D7—99

U.S. Cl. D94—3

FIG. 1

FIG. 2

FIG. 1 is a front elevational view of a flexible drinking straw, showing my new design; and

FIG. 2 is a top plan view thereof.

The rear and bottom views of the drinking straw are the same as the respective front and top views thereof.

This application is a continuation-in-part of application Ser. No. D.7,638, filed June 29, 1967 and now issued as Patent No. D.211,226, dated May 28, 1968.

I claim:

The ornamental design for a flexible drinking straw, as shown and described.
